UNITED STATES PATENT OFFICE

ALBERT R. KUZELEWSKI, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA

HYDRAULIC STEERING GEAR

Application filed March 25, 1931. Serial No. 525,310.

This invention relates to improvements in hydraulic mechanism, and more particularly in hydraulic steering gears of the type employing a motor comprising two rams simultaneously actuated by hydraulic pressure in opposite directions.

One object of my invention is to provide an apparatus of the stated character in which unbalanced stresses and strains are reduced to a practical minimum.

Another object of the invention is to provide an apparatus of the stated character having in itself an inherent stability and which is not dependent upon the foundation structure to provide this essential characteristic.

Still another object of the invention is to provide apparatus of the stated character, characterized by an extreme compactness of form, affording for any given installation a substantial economy in space over that required for a corresponding prior installation.

The invention further resides in mechanical features and details hereinafter more fully described and illustrated in the attached drawings, in which:

Figure 1 is a more or less diagrammatic plan view of an hydraulic steering mechanism made in accordance with my invention;

Fig. 2 is an end elevational, partially sectional, view of the motor assembly; and

Fig. 3 is a view similar to Fig. 2 illustrating a modification within the scope of the invention.

With reference to the drawings, 1 and 2 are rams which operate in two pairs of aligned cylinders, 3—4 and 5—6 respectively, the cylinders 3 and 4 embracing the opposite ends of the ram 1, and the cylinders 5 and 6 the opposite ends of the ram 2. By suitable mechanism, the details of which form no part of the present invention, fluid pressure is applied to the cylinders 3, 4, 5 and 6 through suitable piping 25 and valves 26 and 27 to simultaneously actuate the rams 1 and 2 in opposite directions, and in a desirable installation said fluid pressure may be delivered from one or both of a pair of pumps 7 and 8, which to advantage may be of the reversible discharge type, known as Hele-Shaw, and illustrated

in U. S. Patent No. 1,077,979. These pumps

7 and 8 are individually actuated in the present instance by electric motors 9 and 10. The mechanism as a whole further comprises various devices constituting no part of the present invention for controlling the operation of the pumps and the passage of the fluid pressure to the ram cylinders.

My invention has a particular utility in its application to steering gears, and I have shown the rams 1 and 2 as connected respectively through rods 11 and 12 with the oppositely projecting arms of a yoke 13 carried by a rudder post 14. The rods 11 and 12 are pivotally connected to blocks 15 and 16 respectively, freely adjustable in longitudinal slots 17 in the oppositely projecting arms of the said yoke. Opposite movement of the rams 1 and 2, as described above, accordingly results in an oscillation of the rudder post 14.

It has been customary in apparatus of this type to form the ram cylinders separately and to secure them individually to a base, or foundation, structure by means of bolts, the aligned pairs of cylinders being connected by tie rods. These individual cylinders, or the aligned pairs of cylinders, were inherently unstable and required relatively large foundation structures to provide the necessary stability. Also by reason of the high pressures used in the ram cylinders and the heavy loads applied to the rams, the unbalanced strains and stresses upon the foundation structure were extremely high, and the structure was necessarily made heavy and bulky in order to adequately withstand the heavy pressures.

By reason of these requirements, the overall bulk of the ram and cylinder assembly was relatively great and was correspondingly undesirable for use in vessels where space is at premium. Another undesirable feature of the prior construction lay in the fact that the heavy unbalanced strains had a tendency to shear the foundation bolts.

By the present invention, I take advantage of the simultaneous opposite movements of the rams 1 and 2 to effect a balanced condition which largely eliminates the aforesaid excessive unbalanced stresses and permits the

use of a relatively light foundation structure with a resultant material economy in space. My invention provides an apparatus of the stated character of great compactness of form and correspondingly desirable for use with the steering gears of vessels.

In accordance with my invention, I may form each pair of adjacent cylinders 3-5 and 4-6 in an integral body, preferably forged, see Fig. 2, and in assembly may unite the two integral cylinder bodies in alignment by tie rods 18 passed through lugs 19 at the inner ends of the cylinders. The cylinder assemblies may be mounted as illustrated in Fig. 2, upon a pair of standard I-beams 20, 20, which are in turn suitably secured by bolts to the base structure.

In operation, one cylinder of each integral pairs is under pressure, while the other cylinder is being exhausted, and by reason of the integral construction of the cylinders as described above, the pressures and reactions in one longitudinally aligned pair of cylinders oppose and balance the pressures and reactions in the other aligned pair of cylinders, with the result that the major portion of the unbalanced strain placed upon the structure as a whole, and particularly upon the foundation, is relieved. The combining of the cylinders in integral bodies as described has the natural effect of bringing the cylinders of the aligned pairs relatively close together, and the neutralizing or balancing of the strains, as described, further makes it feasible to reduce the weight and size of the apparatus as a whole and particularly of the supporting under-structure. The cylinder assembly also is inherently stable which permits a still further reduction in size and weight of the foun-

dation structure. This combined effect results in a substantial decrease in the bulk of the ram and cylinder assembly, and as illustrated in Fig. 1, permits the pump and motor assemblies and the associated mechanism to be located immediately adjacent the cylinder assembly within a relatively small space. As previously set forth, this conservation of space is of vital importance in vessels in which the aforescribed apparatus is primarily adapted for use as a steering mechanism.

In Fig. 3, I have illustrated a modification of the construction in which the adjacent parallel cylinders are formed separately, but are bolted together through flanges 21 to form what in effect is an integral structure comprising the two parallel adjacent cylinder bores. There may be other modifications without departure from the invention.

I claim:

In an hydraulic steerer, a pair of substantially parallel rams, a working cylinder operatively associated with each end of each of said rams, means for applying fluid pressure selectively to the cylinders to simultaneously operate the rams in opposite directions, parallel beams constituting supports for the cylinders of the respective rams, tie rods uniting the cylinders of the respective rams, and means independent of said beams for uniting the cylinders at the opposite ends of one of said rams with the correspondingly positioned cylinders of the other rams to thereby effect a substantial balance of the resultant reactions within the ram and cylinder assembly.

ALBERT R. KUZELEWSKI.
